AUTOMATIC VOLUME CONTROL FOR RADIO RECEIVING APPARATUS

Sydney Arthur Stevens and Leslie Ernest Thompson, King's Cross, London, England, assignors, by mesne assignments, to The Union Switch & Signal Company, Swissvale, Pa., a corporation of Pennsylvania

Application September 22, 1934, Serial No. 745,146
In Great Britain September 30, 1933

10 Claims. (Cl. 250—20)

This invention relates to automatic volume control for radio receiving apparatus and has for its object to provide improved arrangements for effecting control of this character.

5 Automatic control of the volume of the reproduced signal in radio-receiving apparatus is usually effected by varying the grid potential relative to the cathode potential of one or more valves of the apparatus in accordance with the 10 strength or amplitude of the received carrier wave so as to render this grid potential increasingly negative as the strength of the carrier wave increases and thus to reduce correspondingly the 15 degree of amplification of the valve which is being controlled.

The variation of the grid potential of the controlled valve for this purpose is generally effected by the provision of a resistance arranged to be traversed by a direct current proportional to the 20 strength of the carrier wave, the potential thereby developed across this resistance being applied to the grid of the controlled valve and it has been proposed to amplify this controlling potential by connecting a second additional resistance in the 25 anode circuit of a valve upon the grid of which a potential derived from the first resistance is impressed, the amplified controlling potential being derived from this second resistance.

In radio-receiving apparatus embodying a detector of the dry surface contact type it is usual 30 to connect a load resistance in the circuit of the detector and according to the principal feature of the present invention the potential across this resistance or any suitable portion thereof due 35 to the rectified current traversing this resistance which is proportional to the strength of the carrier wave is arranged to be applied to the grid of a valve of the apparatus, the current in the anode circuit of this valve being thereby correspondingly modified and a potential derived from 40 this modified anode current being impressed upon the grid of a valve or valves so as to effect an amplified volume control of this valve or valves.

45 Preferably the valve to the grid of which the potential derived from the load resistance is applied is the valve from which the detector is immediately supplied but this valve may be a valve preceding or following the detector supply valve or may be a valve specially provided for the purpose of amplifying the volume control potential derived from the load resistance.

50 Preferably a resistance is connected in the anode circuit of the valve above referred to and the potential across this resistance or a portion

thereof is utilized for varying the grid bias potential of the valve or valves to be controlled.

The grid potential of the valves to be controlled by amplified automatic volume control is determined by the difference of the potential drops across two resistances. By making one of these resistances carry a substantially constant current such as the total anode current of all the valves in the receiving apparatus other than the valve utilized for amplification of the volume 10 control current it is possible to render the potential drop across this resistance substantially constant. The potentials of the cathodes of all the valves except the amplification valve above referred to will thus be substantially constant 15 and positive relative to the H. T. negative terminal. The anode current of the valve which is utilized as an amplification valve for effecting volume control is caused to traverse the other resistance before reaching the H. T. negative terminal and the potential of the positive end of this 20 resistance will then vary with respect to that of the remaining valve cathodes in a manner which will be an amplified reproduction of the potential applied to the grid of this valve. The potential applied to the grid of the valve to be controlled is thus the difference between the potentials due to the potential drops in the two 25 resistances.

The invention is illustrated by way of example 30 in the accompanying drawings Figure 1 of which is a diagrammatic view showing the circuits of a portion of a radio-receiving apparatus embodying one form of the invention, Figures 2 and 3 being similar views of modified circuits embodying 35 other forms of the invention. Figure 4 is a diagrammatic view of the complete circuits of a radio-receiving apparatus embodying a still further modification.

40 Referring now first to Figure 1 it will be seen that a portion of a superheterodyne receiving apparatus is illustrated comprising an I. F. valve V1 which may be the last of a series of I. F. valves and a valve V2 which may be the preceding I. F. valve in the series or the preceding H. F. 45 valve. The valve V1 is shown as comprising an anode 1, a grid 2 and a cathode 3 which is connected through resistances R1 and R2 to the negative H. T. terminal as shown, this terminal being connected to the earth conductor 4 of the 50 apparatus through a resistance R3. The tuned circuit of the anode 1 includes the primary winding 5 of a coupling transformer T1, the secondary winding 6 of which is connected to a detector circuit comprising a detector D of the dry sur- 55

face contact type and a load resistance R_4 one terminal 7 of the resistance R_4 being connected through a wire 8 to a point 9 intermediate the resistances R_1 and R_2 .

5 The valve V_2 similarly comprises an anode 10 the tuned circuit of which includes the primary winding 11 of a transformer T_2 , the grid 12 of the valve V_2 being connected through the secondary winding 13 of a coupling transformer T_3 and a 10 wire 14 to a point 15 intermediate the resistances R_1 and R_2 . The cathode 16 of the valve V_2 is connected through a resistance R_5 to the earth conductor 4. An adjustable point in the load resistance R_4 is connected through wires 17, 18 15 in series with the secondary winding 19 of the transformer T_2 to the grid 2 of the valve V_1 .

It will be understood that the provision of the 20 resistance R_3 causes the potential of the earth conductor 4 to be positive relative to the negative 25 H. T. terminal so that the grid 12 of the valve V_2 when no signal is being received has a suitable normal negative grid bias.

When a signal is being received the mean potential 25 of the grid 12 of the valve V_2 will be the potential at the point 15 transmitted through the wire 14, and the mean potential of the grid 2 of the valve V_1 will be the resultant of the potential of the point 9 and the potential of the adjustable point in the resistance R_4 to which the wire 17 is connected.

30 As the signal strength increases the current traversing the load resistance R_4 will tend to increase but on the other hand the potential applied to the grid 2 from the resistance R_4 by way of wire 17 will become more negative so that the anode current through the valve V_1 will tend to be reduced. This reduced current traversing the resistance R_2 will decrease the drop of potential in this resistance so that an increase in the 35 negative potential of the point 15 will result and this potential transmitted to the grid 12 of the valve V_2 will reduce the anode current of this valve and thus effect the desired amplified volume control.

40 45 It will be understood that the resistance R_3 which is traversed by the anode currents of a number of the valves of the apparatus serves to maintain a normal grid bias for the valves relative to the cathodes connected to the earth conductor 4 and the potential at the point 15 is thus the resultant of the potentials due to the flow of currents in the resistances R_2 and R_3 .

45 Referring now to Figure 2 a modified circuit arrangement similar to that of Figure 1 is illustrated in which delayed amplified automatic volume control is obtained by still further modifying the potential which is impressed upon the grid or grids of the valve or valves to be controlled.

50 For this purpose a resistance R_5 is connected 55 in series with a dry surface contact rectifier M between the earth conductor 4 and the point 15 intermediate the resistances R_1 and R_2 . The wire 14 leading to the grid or grids of the valve or valves to be controlled is in this case connected to a point 19 intermediate the rectifier M and the resistance R_5 .

55 60 With this arrangement the potential derived from the load resistance R_4 is applied to the grid 2 of the valve V_1 as in the apparatus of Figure 1 together with the voltage drop across the resistance R_1 , but in this case the magnitude of the resistance R_2 is such that when the valve V_1 is 65 receiving a weak signal, (so that the voltage drop across the resistance R_4 is small) the grid bias potential applied to the grid 2 is low, and hence the anode current

70 of the valve V_1 is relatively large) the voltage drop across the resistance R_2 will be appreciably in excess of that across the resistance R_3 . Under these conditions the potential of the point 15 will be positive relative to the earth conductor 4. The 75 flow of current from the point 15 through the rectifier M in its reverse direction is however prevented by the rectifier so that since the resistance R_5 is not being traversed by current the potential of point 19 will be that of the earth conductor 4, and hence the only grid bias applied to the preceding valves will be that resulting from the current in their own cathode resistances, such as the resistance R_5 in Fig. 1. For weak signals, therefore, the amplified automatic volume control is inoperative, and is delayed until a signal is received of such magnitude that the anode current of valve V_1 is reduced to a value for which the potential drop across the resistance R_2 becomes the same or less than the potential 80 drop across the resistance R_3 . When this occurs, current will flow from the earth conductor 4 through the resistance R_5 , the rectifier M in its forward direction to the resistance R_2 . The magnitude of the resistance R_5 is so determined 85 as to be much greater than the resistance in the forward direction of the rectifier M . The potential of the point 19 is therefore under these conditions very nearly equal to that of the point 15, and any further increase in signal strength with 90 a corresponding reduction in the anode current of the valve V_1 , will cause the volume control potential transmitted by the wire 14 to be substantially that of the point 15, so that the negative value of this potential will increase as the 95 signal strength increases and will be an amplified reproduction of the grid control potential of the valve V_1 due to the action of the resistance R_4 . In the circuit of Figure 2, therefore simple automatic volume control is applied to the valve V_1 , 40 and delayed amplified automatic volume control is applied to any desired preceding valves. It will be understood that instead of connecting the delay circuit it can if desired be arranged to operate prior to amplification in the circuit between the load resistance R_4 and the grid 2 of the valve V_1 .

Additional amplification of the volume control potential can be effected by providing a resistance in the anode circuit of the controlled valve 50 and deriving from this resistance an amplified potential which is applied to the grid of a preceding valve or valves so that a cascade amplification action is obtained.

The volume control termed "quiet delayed automatic volume control" can also be effected in receiving apparatus embodying the invention in the following manner.

The amplified automatic volume control is effected as above described by the variation in the drop of potential in the resistance connected in the cathode circuit of the control valve such as V_1 , while the quiet control is effected by the change in the potential across a resistance connected in the positive side of the anode circuit 60 of the valve. This potential which is positive relative to the potential of the earth conductor 4 varies in magnitude to a greater extent than the rectified signal voltage across the load resistance R_4 on account of the amplifying action of the valve V_1 and may be used to control the grid bias potential applied to a L. F. valve, and by its considerable magnitude is sufficient to vary the grid 65 bias of the L. F. valve from a value such that the 70

valve passes no anode current at all, down to a point at which the valve operates normally.

In a preferred arrangement for this purpose illustrated in Figure 3 a suitable resistance R6 is interposed in the connection between the positive terminal of the H. T. source and the anode 1 of the detector supply valve V1 utilized for amplification of the automatic volume control, the anode terminal 20 of the resistance R6 being connected through an adjustable resistance R7 connected to earth at E to one terminal 21 of a gas discharge tube N the other terminal 22 of which is connected through a filter resistance R8 to the grid 23 of an L. F. valve V3 of the apparatus, the terminal 22 of the tube N being also connected to the earth conductor 4 through a grid resistance R9.

It will thus be seen that under quiet conditions the grid 23 which is connected to the earth conductor through the resistances R8 and R9 is at earth potential and by applying a positive potential to the cathode 24 a negative grid bias for the grid 23 is obtained.

The cathode 24 of the valve V3 instead of being connected directly to the earth conductor 4 is connected to a point of positive potential relative to earth which is greater than the negative grid bias potential necessary to cause the valve V3 to take a zero anode current. This potential may be obtained in any suitable manner, and as shown in Figure 3 the cathode 24 of the valve V3 is connected through a resistance R10 to a wire 25 which is connected to a point in the cathode resistance of the output valve or some other resistance in the apparatus in such a manner as to impress on the cathode 24 a suitable potential which is positive relative to the potential of the grid 23.

When a weak signal is being received of insufficient strength to be worth reproduction, the voltage drop across the load resistance R4 will be small and the valve V1 will be operating at a low value of grid bias potential determined by the resistance R1, so that its anode current will be relatively large and the potential of the terminal 20 will therefore be low relative to the earth conductor 4 on account of the large voltage drop across the resistance 6. Under these conditions the anode current of the valve V3 will be zero and the valve will not therefore be able to operate as an amplifier. Although therefore the H. F. and I. F. amplifying valves are working at their maximum sensitivity, there will be no audio output from the loudspeaker. When a stronger signal is tuned in, the voltage drop across the load resistance R4 will increase, and the potential of the grid 2 of the valve V1 will become more negative relative to that of its cathode 3. The valve V1 will thus operate to effect simple automatic volume control in the manner above described and will cause amplified automatic volume control to be applied to the preceding valves.

As the anode current of the valve V1 decreases the potential drop across the resistance R6 will also decrease and the potential of the terminal 20 will therefore become more positive relative to the earth conductor 4. The gas discharge tube N connected in the anode circuit between the terminal 20 and the resistance R9 has the effect of preventing the passage of current through this resistance until the potential of the terminal 20 increases to a predetermined value relative to the earth conductor 4 whereupon the tube N will become conducting and current will then pass through the tube and through the resistance R9 to the earth conductor 4. The flow of current

through the resistance R9 will cause a drop of voltage therein rendering the upper end of the resistance R9 positive relative to the earth conductor 4, this potential being applied through the filter resistance R8 and its associated condenser 5 as a grid bias to the grid 23 of the valve V3. The magnitude of the resistance R9 is so proportioned that the grid bias will be greater than the excessive negative bias already applied to the valve V3 as above explained. The grid bias or difference of potential between the grid 23 and the cathode 24 of the valve V3 can under these conditions be arranged to be of the normal value for the valve to operate as an amplifying valve. A further increase in the strength of the received signal will cause the anode current of the valve V1 to be still further reduced and the potential of the terminal 20 will consequently be increased, thus causing an increase in the current traversing the discharge tube N and the resistance R9. This increase of current would have the effect of still further reducing the bias of the valve V3 were it not for the fact that the resulting increase in the anode current of the valve V3 produces an automatic compensation owing to the action of the 25 cathode resistance R10. By suitably proportioning the various resistances in the circuit it can therefore be arranged that all signals above a certain predetermined value which render the discharge tube N conducting will cause the grid bias 30 of the valve V3 to approximate to its correct value for operation as an amplifying valve. Signals of weaker strength than the predetermined value will not be sufficient to increase the potential of the terminal 20 to a value sufficient to cause the 35 discharge tube N to become conducting, and hence the valve V3 will be operating on an excessive negative grid bias and will not pass the unwanted signal.

In order to adjust the predetermined signal strength at which the control 40 shall become operative, the adjustable resistance R7 is provided and this resistance may either be connected between the terminal 20 and earth, as shown in Figure 3, or between the terminal 20 and the H. T. positive terminal depending partly on 45 the characteristics of the discharge tube employed, and also upon the H. T. voltages of the receiving apparatus. It will be observed that the addition of this quiet control circuit in no way alters or interferes with the simple or amplified 50 automatic volume control circuits or their operation.

The neon tube N may, if desired, be so mounted in the apparatus as to be visible and will thus serve as a tuning indicator in the well known 55 manner.

Furthermore, if the valve immediately preceding the detector is arranged to operate on the reflex principle, this valve will serve as an L. F. amplifier in addition to its other functions and the valve being provided with automatic volume control in accordance with the invention low frequency automatic volume control will thus be obtained.

Referring now to the circuit arrangement for 65 a superheterodyne receiving apparatus shown in Figure 4 it will be seen that the aerial A is coupled by means of a band-pass device B to an H. F. amplifying valve V4 which in turn is coupled through a transformer T4 to a combined 70 oscillator-detector valve V5. The anode circuit of the valve V5 is coupled to the grid circuit of a first I. F. valve V6 through a transformer T5, the anode circuit of the valve V6 being similarly 75 coupled through a transformer T6 to the grid

circuit of a second I. F. valve V_1 which serves as a supply valve for the detector D . The load resistance R_4 is connected through an L. F. transformer T_7 to the grid circuit of an output valve V_7 the anode circuit of which is arranged to supply current to the loud speaker (not shown) of the apparatus through a transformer T_{LS} .

The rectifier D is connected in series with the load resistance R_4 and a resistance R_{11} across the terminals of the secondary winding 6 of the transformer T_1 and the terminal 26 of the resistance R_{11} is connected by a wire 27 to an adjustable point 28 in a potentiometer resistance R_{12} one terminal of which is connected to the earth conductor 4 and the other terminal to a point of suitable relatively low potential.

The terminal 29 of the resistance R_{11} is connected by means of a wire 30 through a rectifier M_2 in its reverse current direction to the point 15 intermediate the resistances R_1 and R_2 the point 15 being connected to a volume control wire 14 which is connected to the grid circuits of the valves V_4 and V_6 which are the volume-controlled valves of the apparatus.

The anode 1 of the valve V_1 is connected through a condenser C_1 and a dry surface contact rectifier M_3 to the point 9 intermediate the resistances R_1 and R_2 , the rectifier M_3 being associated with a load resistance S and a potentiometer resistance R_{13} connected between the point 9 and the H. T. positive terminal. The resistance R_{13} enables a delay action to be obtained by applying an adjustable positive potential to the lower end of the resistance S so as to bias the detector M_3 and prevent the detector rectifying received signals of below a predetermined strength.

When signals of sufficient strength are received, a negative potential is built up at the upper electrode of the rectifier M_3 , this potential being transmitted through a filter device consisting of a resistance R_{14} and its associated condenser to the grid 2 of the valve V_1 , thereby applying simple automatic volume control, and by the action of the resistances R_2 and R_3 , as previously described, causing the valve V_1 to operate as an amplifying valve to apply amplified automatic volume control to the preceding valves.

As regards obtaining the quiet control action a relatively large delay voltage is introduced into the circuit of the second detector D , by connecting in the detector circuit a resistance R_{11} across which a fall of potential is produced by tapping off a positive potential from the upper end of resistance R_2 , which for weak signals is arranged to have a potential appreciably higher than that of the earth conductor 4 , so that current will flow from the point 15 through the rectifier M_2 , wire 30 , resistance R_{11} , wire 27 to the earth conductor 4 through the potentiometer resistance R_{12} . The effect of this current will be to make the point 29 positive relative to the point 26 ; some of the current in the circuit will therefore flow through the secondary winding 6 , rectifier D and the resistance R_4 , as the whole of this circuit is in parallel with the resistance R_{11} . If the magnitude of the current thus flowing is arranged to be sufficient, the rectifier D will always be operating on its forward characteristic, and will not therefore rectify even though appreciably large signals may be generated in the windings of the apparatus, owing to the latter operating at its maximum sensitivity. It will be appreciated that these large signals result from the very large amplification of an extremely weak signal received

at the aerial and should not be permitted to reach the loud speaker. When a stronger signal is received, the effect of the circuit including the rectifier M_3 will be to apply a larger control to valve V_1 , and the point at which this control becomes operative can be determined by the amount of delay introduced from the potentiometer resistance R_{13} . One effect of this control voltage is to apply simple automatic volume control to the valve V_1 , a second effect being to apply amplified automatic volume control to the preceding valves, and if desired this amplified volume control may be delayed by a delay circuit consisting of a rectifier M and a resistance R_5 indicated in dotted lines in Figure 4 and operating in the manner already described. The third effect of this control voltage, however, is to reduce the potential of the point 15 below that of the point 28 , so that instead of current flowing through the resistance R_{11} in the direction of the arrow, there is a tendency for the current to reverse. The rectifier M_2 prevents this reversal, so that there is no longer any bias of either polarity applied to the circuit of the second detector D , which then operates in the normal manner. It will be evident that by suitably proportioning the values of the resistances the detector circuit can be made to function at any desired signal strength.

In order to prevent a received signal of temporarily very low value due to "fading" from failing to be transmitted, a condenser C of relatively large capacity is connected across the terminals of the resistance R_{11} as shown.

The receiving apparatus of Figure 4 is shown as provided with terminals P. U. for connection to the pick-up device of a gramophone and when the apparatus is being employed for the reproduction of gramophone records the I. F. valve V_1 is utilized as a first L. F. amplifying valve in the well-known manner, switches S_1 and S_2 being under these conditions adjusted from the positions shown in full lines to the positions shown in dotted lines.

In all the circuits above described embodying the invention it will be noted that simple automatic volume control is arranged to be supplied to a valve such as the last I. F. valve which is subject to a relatively high voltage so that a high control potential cannot be impressed thereon without risk of distortion in operation. The amplified volume control, on the other hand is arranged to be applied to an earlier valve or valves of the receiving apparatus which being subject to relatively lower voltages is capable of having relatively high control potential impressed thereon without distortion.

The invention is evidently not limited to the particular circuit connections above described and illustrated by way of example which may be varied in many respects without exceeding the scope of the invention.

Having now particularly described and ascertained the nature of our said invention and in what manner the same is to be performed, we declare that what we claim is:—

1. In receiving apparatus embodying a plurality of electron amplifying valves and a detector the combination comprising, a first resistor connected in the load circuit of said detector, a first circuit means to connect at least a portion of said resistor across the grid and cathode of the valve immediately preceding the detector to effect simple automatic volume control for that valve, a current source having its positive

- terminal connected to the anodes of said valves, a ground conductor connected to the cathode of each of the valves ahead of the valve supplying the detector, a second resistor interposed between the negative terminal of the source and the cathode of the valve supplying the detector, a third resistor interposed between the negative terminal of the source and said ground conductor to create a given potential for said conductor, and another circuit means connected with the grid of at least one valve ahead of the valve supplying the detector and including an asymmetric unit connected between the ground conductor and the terminal of said second resistor remote from the negative terminal of the source and said unit disposed with its forward direction toward said terminal of the second resistor to effect delayed amplified automatic volume control for said other valve.
2. In receiving apparatus embodying a plurality of electron amplifying valves and a detector the combination comprising, a resistor connected in the load circuit of said detector, circuit means to connect at least a portion of the resistor across the grid and cathode of the valve immediately preceding the detector to effect simple automatic volume control for that valve, a current source for the anode circuits of said valves, a second resistor interposed in the anode circuit of said preceding valve between the negative terminal of the current source and the cathode, a third resistor interposed between the negative terminal of the source and the cathode of another one of said valves, and another circuit means including a fourth resistor and an asymmetric unit connected between the terminals of said second and third resistor remote from the source to effect delayed amplified automatic volume control for said other valve.
3. In receiving apparatus embodying a plurality of electron amplifying valves and a detector the combination comprising, means to establish a normal negative grid bias potential for the valve immediately preceding the detector, means including a first resistor interposed in the load circuit of said detector and having connection to the grid of said preceding valve to establish simple automatic volume control for that valve, a source of anode current for said valves, a second resistor interposed between the negative terminal of the source and the cathode of said preceding valve, a third resistor interposed between the negative terminal of the source and the cathode of another one of said valves, said second and third resistor characterized by the normal potential drop across the third resistor being less than that across the second resistor, a connection including a fourth resistor and an asymmetric unit between the terminals of said second and third resistor remote from the current source and with the forward direction of said unit toward the terminal of the second resistor, and means to connect the terminal between said unit and the fourth resistor with the grid of said other valve whereby delayed amplified automatic volume control for said other valve is effected.
4. In receiving apparatus embodying a first and a second electron amplifying valve and a detector the combination comprising, means interposed in the grid circuit each valve to effect a normal negative grid bias potential, a source of current for the anode circuits of the valves, a first resistor interposed between the negative terminal of the source and the cathode of the second valve, a second resistor interposed between the negative terminal of the source and the cathode of the first valve, said resistors characterized by the normal potential drop across said first resistor being greater than that across said second resistor, a circuit connection including a third resistor and an asymmetric unit connected between the terminals of said first and second resistors remote from the source and with the forward direction of the unit toward the terminal of the first resistor, means including a resistor in the load circuit of the detector for applying a potential between the terminal of the first resistor remote from the source and the grid of said valve, and other means to connect the terminal between said unit and the third resistor with the grid of the first valve.
5. In receiving apparatus including a high frequency amplifying valve, a detector and a low frequency amplifying valve the combination comprising; a first resistor interposed in the load circuit of the detector, means to connect at least a portion of said resistor with the grid of the high frequency tube to effect automatic volume control of that valve, a second resistor interposed in the anode circuit of said high frequency valve, means to establish a normal negative grid bias potential for the low frequency valve and characterized by effecting substantially normal zero anode current of that valve, circuit means including a resistor and a gas discharge tube connected between the terminal of said second resistor toward the anode of the associated valve and the grid of the low frequency valve, and means including a source of alternating signaling current connected with the grid of the high frequency valve to vary the potential of said grid with respect to the cathode in accordance with said signaling current whereby the potential applied to said circuit means is varied to modify the normal negative grid bias potential of the low frequency valve to effect amplification of the output of the detector.
6. In receiving apparatus embodying a high frequency valve, a detector and a low frequency valve the combination comprising; a grid circuit for the low frequency valve connected between the grid and a ground conductor, said circuit including two resistors and a winding inductively coupled with the output of the detector, means connected between the cathode of the low frequency tube and such ground conductor to effect a quiet grid bias that gives substantially zero anode current, a resistor and a winding serially interposed in the anode circuit of the high frequency valve with said winding inductively coupled with the input of the detector, means including a source of alternating signaling current connected with the grid of the high frequency valve, and another circuit means including a discharge tube connected between the terminal of the last mentioned resistor toward the anode of the high frequency valve and the mid terminal of the two resistors of the grid circuit of the low frequency valve whereby the potential effected by the current of the anode circuit of the high frequency valve on said discharge tube in response to said signaling current is operative to modify the grid bias of the low frequency valve.
7. In receiving apparatus embodying a high frequency valve, a detector and a low frequency valve the combination comprising; a grid circuit for the low frequency valve including a winding coupled with the output of the detector, means including a source of potential connected with

said grid circuit and characterized by establishing a quiet grid bias potential that effects substantially zero anode current, and anode circuit for the high frequency valve including a 5 winding coupled with the input of the detector, means including a source of alternating signaling current connected with the grid of the high frequency valve, and a circuit means including a discharge tube connected between a point of varying 10 potential of the anode circuit of the high frequency valve and the grid circuit of the low frequency valve to modify the quiet grid bias potential in response to the signaling current applied to the high frequency valve whereby amplification of such signal energy after detection is 15 effected.

8. In receiving apparatus including a high frequency amplifying valve, a detector and a low frequency valve the combination comprising; a 20 first circuit means including a source of alternating signaling current coupled with the grid circuit of the high frequency valve, a second circuit means including a first and a second resistor as well as the detector and a winding, said winding 25 coupled with the anode circuit of the high frequency valve to inductively receive an electromotive force in response to the amplified signaling current, grid circuit means for said low frequency valve and including said first resistor, 30 and other circuit means including a rectifier and a current source connected across said second resistor, said rectifier disposed to pass current which flows in said second resistor in a direction 35 opposite to that supplied through the detector in response to the electromotive force induced in the winding of said second circuit means whereby the detector operates on its forward characteristic and quiet automatic volume control for the low frequency valve is effected.

40 9. In receiving apparatus including a high frequency amplifying valve, a detector and a low frequency valve the combination comprising; a first circuit means including a source of alternating signaling current coupled with the grid circuit of the high frequency valve, a second circuit means including a first and a second resistor as well as the detector and a winding, said winding 45 coupled with the anode circuit of the high frequency valve to inductively receive an electromotive force in response to the amplified signaling current, a third circuit means including a first rectifier and a load resistor connected between the anode and cathode of the high frequency valve, said rectifier disposed with its forward 50 direction toward the cathode, means to connect said load resistor with the grid of the high frequency valve to effect automatic volume control for said valve in response to variations effected in the current supplied to the anode of said valve, grid circuit means for said low frequency valve 55 and including said first resistor, and a fourth circuit means including a second rectifier and a current source connected across said second resistor, said second rectifier disposed to pass current which flows in said second resistor in a direction opposite to that supplied through the detector in response to the electromotive force induced in the winding of said second circuit means whereby quiet automatic volume control for the low frequency valve is effected.

frequency valve and including said first resistor, and a fourth circuit means including a second rectifier and a current source connected across said second resistor, said second rectifier disposed to pass current which flows in said second resistor in a direction opposite to that supplied through the detector in response to the electromotive force induced in the winding of said second circuit means whereby the detector operates on its forward characteristic and quiet automatic volume control for the low frequency valve is effected. 5

10. In receiving apparatus including a first stage and a second stage high frequency valve, a detector and a low frequency valve the combination comprising; a first circuit means including a source of alternating signaling current coupled with the grid circuit of the first stage high frequency valve, a second circuit means including a first and a second resistor as well as the detector 15 and a winding, said winding coupled with the anode circuit of the second stage high frequency valve to inductively receive an electromotive force in response to the amplified signaling current, a third circuit means including a first rectifier and 20 a load resistor connected between the anode and cathode of said second stage valve, said rectifier disposed with its forward direction toward the cathode, means to connect said load resistor with the grid of said second stage valve to effect 25 automatic volume control for that valve in response to variations effected in the current supplied to the anode of said second stage valve, a source of current having its positive terminal connected with the anodes of said valves, a ground conductor connected with the cathode of said first stage valve, a third and a fourth resistor connected between the cathode of said second stage valve and the negative terminal of 30 said current source, a fifth resistor interposed between the ground conductor and the negative terminal of the current source, means to connect the mid terminal of the third and fourth resistors with the grid of said first stage valve to effect 35 automatic volume control for that valve in response to variations effected in the current supplied to the anode of said second stage valve, grid circuit means for said low frequency valve and including said first resistor, and a fourth circuit means including a second rectifier and a 40 current source connected across said second resistor, said second rectifier disposed to pass current which flows in said second resistor in a direction opposite to that supplied through the detector in response to the electromotive force 45 induced in the winding of said second circuit means whereby quiet automatic volume control for the low frequency valve is effected. 50
